WAD SORTING MACHINE.

No. 375,509.

Patented Dec. 27, 1887.

UNITED STATES PATENT OFFICE

PRENTISS SELBY, OF OAKLAND, CALIFORNIA.

WAD-SORTING MACHINE.

SPECIFICATION forming part of Letters Patent No. 375,509, dated December 27, 1887.

Application filed August 2, 1887. Serial No. 245,980. (No modcl.)

To all whom it may concern:

Be it known that I, PRENTISS SELBY, of 5
Oakland, Alameda county, State of California,
have invented an Improvement in Wad-Sort-
ing Machines; and I hereby declare the follow-
ing to be a full, clear, and exact description of
the same.

My invention relates to a device for sorting
wads which are used in loading cartridges, in
10 order that the varying thicknesses of wads
may be separated from each other and each
grade of wads may be used together, so that the
loads in the shells may have an absolute uni-
formity in every respect.

15 It consists of a vertical receiver into which
the wads are placed, a segmental swinging
shoe moving beneath the receiver and acting
to carry the wads forward one by one as they
fall from the receiver, together with a rotating
20 table having radially extending arms with
clamps or holders at their outer ends, beneath
which the wads are deposited by the moving
shoe, and a cam which acts upon these rods so
as to deposit the wads into the proper recep-
25 tacles, which are arranged around a periphery
of the table.

Referring to the accompanying drawings for
a more complete explanation of my invention,
Figure 1 is an elevation of my machine, show-
30 ing half of the rotating table in section. Fig.
2 is a plan view of the same. Figs. 3 and 4
show the devices for filling the tubes.

35 A is a vertical tubular receiver of consider-
able length and of sufficient size to receive
wads of the proper diameter, and B is a table
revolved by any suitable mechanism so that
its periphery will be near the receiver. A se-
40 ries of radial arms, C, extend from the inner
circumference of the rotating table B, through
suitable guides, to the outer periphery, and
upon the outer ends of these arms are the ver-
tical bars or holders D, between which and the
45 vertical side of the table B the wads E are
held, as shown in Figs. 1 and 2.

50 F is the rubber or other elastic spring, which
is shown in the present case as passing over a
pin, G, upon the outer end of the arm C or
upon the vertical part D, and the inner end of
this spring is attached to a similar pin, H,
55 upon the top of the table. This spring pro-
duces a sufficient tension, so that when a wad

is deposited beneath the arm D the tension of
the spring will press it against the side of the
table B and hold it there until released.

55 I is a slotted weight moving up and down
upon the guide-pin J, and having the legs K
extending downward so as to rest upon the
upper edge of the wad B; and when the hold-
ing-arm D is pushed away from the wad the
60 weight will act to force the latter downward
and prevent its sticking. When released, the
wads drop into the chambers or receptacles
(shown at L) around the periphery of the table,
and these chambers have the inclined outlet-
65 tubes M, through which the sorted wads may
be discharged into the proper receivers.

70 N is a cam fixed to a central stationary shaft
in such a position that the inner ends of the
radial sliding bars C may come in contact with
it at the proper time. This time will depend
on the thickness of the wad which is held be-
75 neath the arm D.

If a thin wad is held beneath the arm D the
inner ends of the arm C will be drawn inward
80 by the spring F, so that as the table B rotates
the inner end of the arm C will strike the cam,
and as it is pressed outward by the incline
of the cam it forces the arm D away, so as to
release the wad E, and the weight I acts suffi-
85 ciently to press the wad down, in case it should
stick a little, and cause it to drop into the re-
ceptacle L, over which it happens to be at the
time of its release.

90 If the wads are thicker beneath some of the
arms D, it is manifest that, as the inner end
of the sliding bar C is farther away from the
center on account of this thicker wad, it will
strike the cam N at a later point, and the thick
wads will thus be dropped into receptacles
95 which are farther along than those into which
the thin ones will fall.

99 In order to place the wads beneath the
holder D, I have shown a segment, O, which
is pivoted to or on a pin passing through the
hole P, and the outer periphery of the segment
fits into a corresponding curve in the base or
frame Q, which supports it. This segment is
placed beneath the tube A, which holds the
wads, so that when drawn back one wad will
fall upon the curved floor or base Q in front
of the point of the segment. When the seg-
ment returns, it pushes this wad forward and

upward, thus forcing it beneath the arm D, by which it is held, the wad sliding up beneath the arm, so as to stand edgewise, as shown in Fig. 1. The segment O is caused to 5 oscillate about its pivot-pin by means of a crank-wheel, R, connected by a pitman, S, with a vertically-moving slide, T, traveling upon the guide U. A link or pitman, V, connects this slide with the segment O, and thus 10 causes it to oscillate about its pivot-point, so as to allow the wads to drop one by one in front of the segment, and thus be forced between the holding-arms D and the side of the rotating table B. As the oscillations of the 15 segment are produced by the rotation of the crank-wheel R, and this is mounted upon a shaft which is driven by the beveled gearing W from the rotating table B, it will be seen that the movements of the segment may be 20 timed so as to be exactly with the rotation of the table and the instant when the arms D are presented to receive one of the wads. These wads are then held by the arms D, and as the table rotates are dropped by the action of the 25 cam N, as before described, into their various receptacles.

In order to fill the tubular receiver A, I have employed a tube, X, having a projecting lip, Y, and having slots along the side, as 30 shown at Z, so that the interior may be seen, to know whether the tube is properly filled, and also for the purpose of assisting in putting the wads in, in case they should not pass in readily. The wads are placed in a sort of 35 trough, a, and the tube X, which is closed at one end, is taken by the operator, and the projecting scoop-shaped point Y is moved beneath the wads in the trough a, so that they will slide into the tube and fill it instantly. 40 This tube is then inserted into the receiving-tube A and the wads deposited in a perfectly regular manner without getting upon edge or otherwise obstructing the tube.

Having thus described my invention, what 45 I claim as new, and desire to secure by Letters Patent, is—

1. A wad-sorter consisting of a rotary table having the radially-sliding arms C, provided with the vertical bars or holders and spring, 50 whereby the wads are held between the holder

and the side of the table, in combination with a stationary cam so arranged that as the table rotates the inner ends of the arms will be brought into contact with the cam, and they will be forced outward, so as to release the 55 wad, substantially as herein described.

2. The stationary cam centrally placed, a table rotating outside of said cam and around its common center, said table being provided with spring-actuated holding arms or plates, 60 beneath which the wads may be inserted and held, and sliding arms which are actuated by the cam to release the wads, substantially as herein described.

3. The sliding spring-actuated holding arms 65 or plates, beneath which the wads are received and retained until released by the action of the cam, the vertically-moving weight, by the pressure of which the wads are prevented from sticking when released, in combination with 70 the cam, the rotary table, and the releasing arms or bars acted upon by the stationary cam, the chambers or receivers placed in line beneath the wad-holding plates and having discharge tubes or openings, substantially as 75 herein described.

4. The rotary table, with the spring-actuated holding arms or plates and the releasing-cam, as shown, in combination with a reservoir, the vertical wad-supplying tube or receiver, and the oscillating segment, whereby 80 the wads are removed from the reservoir and placed beneath the holding-plates successively, substantially as herein described.

5. The vertical wad-holding receiver or 85 chamber A, the holding plates or arms, the rotating table, the concave-curved floor or base situated beneath the lower end of the receiver, and the correspondingly-curved arc or segment, by which it is oscillated, so as to allow 90 the wads to fall singly from the receiver in front of the segment and be placed by the segment beneath the holding plates or arms, substantially as herein described.

In witness whereof I have hereunto set my 95 hand.

PRENTISS SELBY.
